UNITED STATES PATENT OFFICE.

WALTER LYTTON, OF CHICAGO, ILLINOIS.

LOUD SPEAKER.

Application filed March 21, 1923. Serial No. 626,455.

This invention relates to improvements in loud speakers for radio receiving sets, and it has for one of its objects the production of an improved loud speaker, particularly with reference to the relation of the sound reproducer diaphragm of the speaker and the electro-magnetic devices associated therewith. Other objects of the invention will be apparent upon a consideration of the accompanying drawings and the following description thereof.

Of the accompanying drawings, Fig. 1 is an elevation of a loud speaker which embodies the features of my invention; Fig. 2 is an enlarged vertical central section of the same; and Fig. 3 is a transverse section thereof along the line 3—3 of Fig. 2.

The loud speaker comprises a casing 10 and a sound delivering horn 11. Within the 20 casing is positioned a magnetic system 12 comprising a central pole 13 and side poles 14, the poles being connected by the magnetic circuit comprising the side bars 15, the base 16, to which the side bars are connected in any suitable manner, and the central post 17. The diaphragm 18 of the loud speaker is composed of any suitable material, but I prefer for the purpose an iron or steel diaphragm; and projecting from the 30 diaphragm is an armature 19 fixed to the diaphragm in any suitable manner such as by being riveted thereto. This armature extends downwardly towards the pole 13. Between the diaphragm and the pole 13 is mounted a coil of wire 20, the terminals 21 of which are adapted to be connected to the output circuit of a radio receiving set in the ordinary manner. The magnetic system may be a permanent or an electro- 40 magnetic system as may be desired. I prefer for the purpose a permanent magnetic system. The diaphragm is properly mounted on the upper end of the casing in any suitable manner. I prefer to clamp it 45 between the ring 46 and the annular flange 47 of the cap 48 which is screwed on to the casing 10.

As is well understood the audio pulsations of the output circuit of the receiving 50 system, when the coil 20 is properly connected therewith, will cause material variations in the current flowing through the coil, and this in turn will cause corresponding variations in the strength of the magnetic field flowing across from the pole 13

to the poles 14 through the armature 19 and the diaphragm 18. Normally the magnetic field will pull the diaphragm downwardly somewhat due to the magnetic pull thereon, but the force of this pull will be varied materially by the magnetic effect of the pulsations of the coil and this will produce sound vibrations of the diaphragm. By the arrangement described I provide a very powerful and sensitive varying electro-magnetic system underneath the diaphragm so that the pulsations in the coil 20 are transformed into loud sounds and the sounds produced are not distorted by the producing mechanism. The sound is transmitted from the diaphragm in an ordinary manner through the horn 11.

In order to increase the power and sensitivity of the apparatus I provide sensitive and convenient adjusting means for varying the position of the coil 20, and of the pole 13, with reference to the diaphragm 18 and the armature 19. The coil is adjustably threaded on to the end of a magnetic bar 22, the upper end of which forms an extension of the pole 13, and this end 28 may be considered as the effective pole. The bar 22 extends downwardly through the center of the post 17, and its lower end is supported by a thumb screw 23. A spring 24 at all times forces the end of the bar downwardly against the screw. Obviously by adjusting the position of the screw 23 with reference to the base 25 of the casing 10 the position of the pole 28 and also of the coil 20 with reference to the diaphragm and armature are adjusted. By this means contact of the armature 19 and the pole 28 may be avoided and at the same time the air gap between the two may be reduced to a minimum. And by adjusting the position of the coil 20 on the end of the bar 22 the position of the coil and the end 28 may be relatively changed with relation to the diaphragm and armature.

In order to reproduce the sounds more nearly normally I provide a horn 11 which comprises the conical standard 26 to the upper end of which is mounted the mouth piece 27. In order to produce strength and prevent any vibrating tendency of the sides I prefer to have the standard made of a metal such as brass. But the mouth piece 27 I prefer to have of a non-metallic material such as vulcanite, as this reproduces

the sound more nearly in harmony with the original sounds.

I claim as my invention:

1. A sound reproducer comprising a magnet having a central post, a wall surrounding said post, a base connecting said post and wall at their lower ends, a casing surrounding said magnet, a diaphragm mounted in said casing over the upper end 10 of said wall, an armature fixed to the central portion of said diaphragm and projecting therefrom towards said post, all of said elements being composed of magnetic material; in combination with a coil surrounding 15 said armature and positioned above the upper end of said post, the terminals of said coil being adapted to be connected with the output circuit of a radio receiving set.
2. A sound reproducer comprising a magnet having a central post, a wall surrounding said post, a base connecting said post and wall at their lower ends, a casing surrounding said magnet, a diaphragm mounted in said casing over the upper end 20 of said wall, an armature fixed to the central portion of said diaphragm and projecting therefrom towards said post, all of said elements being composed of magnetic material; in combination with a coil surrounding 25 said armature and positioned above the upper end of said post, the terminals of said coil being adapted to be connected with the output circuit of a radio receiving set, the upper end of said post 30 passing into said coil.
3. A sound reproducer comprising a magnet having a central post, a wall surrounding said post, a base connecting said post and wall at their lower ends, a casing surrounding said magnet, a diaphragm mounted in said casing over the upper end of said wall, an armature fixed to the central portion 35 of said diaphragm and projecting therefrom towards said post, all of said elements being composed of magnetic material; in combination with a coil surrounding 40 said armature and positioned above the upper end of said post, the terminals of said coil being adapted to be connected with the output circuit of a radio receiving set, and a member slidably mounted in 45 said post, and projecting slightly into said coil.
4. A sound reproducer comprising a magnet having a central post, a wall surrounding said post, a base connecting said post and wall at their lower ends, a casing surrounding said magnet, a diaphragm mounted in said casing over the upper end of said wall, an armature fixed to the central portion 50 of said diaphragm and projecting therefrom towards said post, all of said elements being composed of magnetic material, the upper end of said post comprising a member slidably mounted in the main por-

tion of said post, and means for adjusting the position of the upper end of said post with reference to said armature, said coil being threaded onto the upper end of said 70 slideable member.

5. A sound reproducer comprising a magnetic circuit consisting of a central post, a side wall, and a base connecting said post and wall, a diaphragm mounted on the upper end of said wall, and a member mounted 75 for relative longitudinal movement in said post, all of said elements being composed of magnetic material, and a coil fixed to the upper end of said slideable member and positioned adjacent said diaphragm, the terminals of said coil being adapted to be connected to the output circuit of a radio receiving set.

6. A sound reproducer comprising a magnetic circuit consisting of a central post, a side wall, and a base connecting said post and wall, a diaphragm mounted on the upper end of said wall, and a member mounted 80 for relative longitudinal movement in said post, all of said elements being composed of magnetic material, and a coil fixed to the upper end of said slideable member and positioned adjacent said diaphragm, the terminals of said coil being adapted to be connected to the output circuit of a radio receiving set, and an armature projecting 85 downwardly from the central portion of said diaphragm and into said coil.

7. A sound reproducer comprising a magnetic circuit consisting of a central post, side wall, and a base connecting said post and wall, a diaphragm mounted on the upper end of said wall, and a member mounted 100 for relative longitudinal movement in said post, all of said elements being composed of magnetic material, and a coil fixed to the upper end of said slideable member and positioned adjacent said diaphragm, the terminals of said coil being adapted to be connected to the output circuit of a radio receiving set, and an armature projecting 105 downwardly from the central portion of said diaphragm and into said coil, and means for adjusting the position of said slideable member with reference to said armature.

8. A sound reproducer comprising a casing, a magnet mounted in said casing and having its two poles adjacent the upper end thereof, a sound reproducer diaphragm mounted adjacent the ends of said two poles with its central portion adjacent one of said poles, a member mounted for relative longitudinal movement in said latter pole, means for varying the strength of the magnetic field between said poles, and means for adjusting the position of said member with reference to said diaphragm, said means comprising a screw threaded into the bottom of said casing and projecting up- 110 115 120 125 130

wardly into said post, the lower end of said slideable member being positioned on the upper end of said screw.

9. A sound reproducer comprising a casing, a magnet mounted in said casing and having its two poles adjacent the upper end thereof, a sound reproducer diaphragm mounted adjacent the ends of said two poles with its central portion adjacent one of said poles, a member mounted for relative longitudinal movement in said latter pole, means for varying the strength of the magnetic field between said poles, and means for

adjusting the position of said member with reference to said diaphragm, said means comprising a screw threaded into the bottom of said casing and projecting upwardly into said post, the lower end of said slideable member being positioned on the upper end of said screw, and a spring positioned in said post arranged to continuously press said slideable member downwardly onto said screw.

In testimony whereof, I hereunto set my hand.

WALTER LYTTON.
